UNITED STATES PATENT OFFICE.

CARL ERNST, OF ROCHESTER, NEW YORK.

DRAWER-SUPPORT FOR FILING-CASES.

No. 823,771.

Specification of Letters Patent. Patented June 19, 1906.

Application filed May 4, 1905. Serial No. 238,782.

To all whom it may concern:

Be it known that I, CARL ERNST, of Rochester, in the county of Monroe and State of New York, have invented certain new and useful Improvements in Drawer-Supports for Filing-Cases; and I do hereby declare the following to be a full, clear, and exact description of the same, reference being had to the accompanying drawings, forming a part of this specification, and to the reference-numerals marked thereon.

My present invention relates to improvements in devices for supporting the drawers of filing-cases, desks, or other furniture; and the purpose of my invention is to provide improved means for supporting the drawers, particularly those of large capacities, in such a way that they may be easily withdrawn and replaced within the filing-case with a minimum friction and without liability of sagging as they are extended to the forward limit of their motion, even though the drawers may be heavily loaded.

To these and other ends the invention consists in certain improvements and combinations of parts, all as will be hereinafter more fully explained, the novel features being pointed out in the claims at the end of the specification.

In the drawings, Figure 1 is a view of a section of a filing-case having drawer-supporting devices constructed in accordance with my invention applied thereto, the upper drawer being shown in closed position and the lower drawer being shown withdrawn from the casing. Fig. 2 is a longitudinal section through the drawer, showing the latter withdrawn from the filing-case. Fig. 3 is a transverse sectional view through the drawer and case on the line 3-3 of Fig. 1. Fig. 4 is a perspective of the extension-support, showing the cooperative relation of the latter and the drawer and casing; and Fig. 5 is a perspective view showing the cooperative relation of the extension-support and the drawer. The same numerals of reference in the several figures indicate similar parts.

My invention is capable of being applied to drawers of various articles of furniture, the present embodiment of the invention, as shown in the drawings, being applied to an ordinary filing-case embodying the casing 1, having vertical sides 2 to receive the drawer between them, and on these vertical portions of the casing are secured the horizontal guides of ways 3, the latter extending from

front to back and at either side of the drawer-receptacle, and on each of these guides are formed the upper and lower tracks 4 and 5, respectively, which extend in a direction longitudinal of the drawer-receptacle, the upper track 4 being provided with a longitudinal guiding-groove 6, at its side adjacent to the casing. Secured to the uprights 2 at the front of the drawer-receptacle are the bearings 7, which for the purpose of reducing or preventing friction are provided with the rollers 8, an upwardly-extending projection 7^a being provided on each bearing above the surface of the adjacent roller for a purpose that will presently appear.

Into the drawer-receptacle beneath the guides 3 are mounted the sliding extension-supports 9, one at either side of the receptacle, each support being provided with a bracket 10 at its upper rear corner in which the roller 11 is journaled in such a way that it will run upon the track 5 at the under side of the guide 3, the flange of the roller being arranged to run in the groove 6 of the guide as the support is moved into and out of the drawer-receptacle, and extending upwardly from each support 9 is an offset bracket 12, having a flanged roller 13 journaled therein to run upon the track 4 at the upper side of the guide 3, the flange of the roller being arranged to run in the groove 6 of the guide as the support is moved longitudinally, and this will prevent the lateral displacement of the supports relative to their respective guides in one direction, while the bracket 12, cooperating with the opposite surface of the guide, will prevent binding between the movable support and the casing. The lower edge of each of the extension-supports is provided at its inner side with a groove 14 to receive the projection 7^a, and this arrangement allows the movable support to be moved over the roller 8 in a direction longitudinally of the drawer-receptacle, while the projection 7^a of the bearing 7, resting in the groove 14, will guide the movable support, and thus prevent the latter from being displaced from the side of the drawer-receptacle.

The drawer (indicated by the numeral 15) is fitted between the extension-supports 9 and in the present instance is provided with a bearing 16, having a roller 17 journaled therein and arranged to run upon the longitudinally-extending track 18, which is formed on the forward portion of the support 9, a projection 17^a from the bearing 16 resting in a longitudinal groove 19 in the adjacent sup-

port to prevent separation of the supports and the drawer. This roller 17 is preferably arranged near the center of the drawer in order that it may sustain most of the weight thereof, a staple or projection 20 being provided near the rear of the drawer on either side thereof to operate in the longitudinal grooves 21 of the corresponding supports to prevent tilting of the drawer.

- 10 Forward motion of the drawer relatively to the supports 9 is limited by the co-operatively-arranged abutments 22 and 23, arranged, respectively, on the drawer and on the supports, and forward motion of the extension-supports relatively to the casing is limited by the relatively fixed abutment 24, which is arranged, preferably, on the guides 3 in such a position as to co-operate with the bracket 12, which carries the roller 13 of the movable support.

The drawers of filing-cases and similar furniture when supported in accordance with my invention may be withdrawn and returned to their cases with the slightest effort, even though they may be heavily loaded with documents, as all of the relatively movable parts have a rolling engagement with each other, and in operating the drawer it will move in a straight line and cannot sag as it approaches the forward limit of its motion, as the rear ends of the movable supports are suspended by the rollers 13 and the forward portions are supported by the rollers 8, while the rollers 11, running on the lower track 5 of the guides, prevent the forward ends of the supports from tilting downward, the series of guiding-tracks thus formed positively limiting the vertical motion of the parts, and by means of the guiding-grooves in the guides and supports lateral displacement of the various parts is positively prevented, unless the drawer is lifted out of its normal position between the movable supports, and this will allow the parts to be removed from the casing; but normally the drawer will serve to prevent displacement of the movable supports and will in turn be guided between them.

In withdrawing the drawer from the casing the drawer and supports usually move forwardly bodily until the brackets 12 of the supports engage the stops or abutments 24 of the casing, when the forward motion of the supports will be arrested and continued motion of the drawer will cause the latter to move forwardly on the supports until the abutments 22 of the drawer co-operate with the corresponding abutments 23 at the forward ends of the supports, and at this point the drawer and the supports are at the limit of their forward motion. In returning the drawer to the casing the front board of the drawer, which usually projects from the sides thereof, will engage the forward ends of the supports after the drawer has moved rearwardly thereon and continued motion of the

parts rearwardly will cause the drawer and supports to be returned bodily into the casing.

By arranging the guides and the extension-supports at either side of the drawer the latter will be more evenly suspended than is the case where the supports are arranged beneath the drawer, and in forming the grooves 6, 14, and 19 in the guides and supports to receive the guiding devices considerable space is economized, so that the sides of the drawer may fit very closely within the casing, as the supports require a very narrow space in which to operate.

In providing a rolling engagement for the relatively movable parts of the device friction and wear are positively eliminated, and therefore drawers equipped with supporting means embodying my invention will fit closely within their casing and will not bind from warping and similar causes, and as the guiding-tracks form a series of ways which will positively prevent relative vertical motion between the parts and the guiding-grooves and their co-operating parts limit the lateral motion thereof proper operation of the drawer and its parts are insured at all times.

I claim as my invention—

1. The combination with a casing having a drawer-receptacle therein, a drawer adapted to operate in the receptacle and horizontal ways on the casing, of sliding supports for the drawer arranged to operate beneath said ways and having bearings upon opposite sides of the ways.

2. The combination with a casing having a drawer-receptacle therein, a drawer adapted to operate in the receptacle and guides on the casing, of sliding supports for the drawer having rollers operating on tracks upon opposite sides of the guides.

3. The combination with a casing having a drawer-receptacle therein, a drawer adapted to operate in the receptacle and guides on the casing, of a pair of sliding supports arranged between the sides of the drawer and the casing, having rollers engaging the upper sides of the guides, and rollers arranged at the front of the receptacle and bearing on the under sides of the supports.

4. The combination with a casing having a drawer-receptacle therein, a drawer adapted to operate in the receptacle and ways on the casing, of sliding supports for the drawer guided by said ways and having grooves on their under sides, rollers arranged at the front of the receptacle and bearing on the under sides of the supports and means co-operating with the grooves in the supports for preventing lateral displacement of the latter.

5. The combination with a casing having a drawer-receptacle therein, a drawer adapted to operate in the receptacle, guides on the casing having grooves therein, and sliding supports for the drawer having grooves on the

under sides thereof, of flanged rollers on the supports engaging the grooves in the guides, rollers arranged near the front of the receptacle and coöperating with the under sides of the supports, and devices engaging the grooves in the supports to prevent lateral displacement of the latter.

6. The combination with longitudinal supports having tracks and a drawer movable with relation thereto, of bearings attached to the drawer provided with extensions having lateral engagement with the supports to prevent displacement of the drawer and supports, and rollers journaled on said bearings and coöperating with the tracks of said supports.

7. The combination with horizontal supports having tracks provided with grooves, and a drawer movable longitudinally thereof, of bearings supported on the sides of the drawer having projections coöperating with said grooves, to prevent lateral disengagement of the drawer and supports, and rollers journaled in the bearings and arranged to operate in said tracks.

8. The combination with the casing having a drawer-receptacle therein, a drawer adapted to operate in the receptacle, and movable supports mounted to operate in the drawer-receptacle having ways thereon and guiding-grooves extending longitudinally thereof, of supporting-rollers carried by the drawer and arranged to operate on the ways of the supports, and projections on the drawer arranged to operate in the guiding-grooves of the supports for preventing tilting motion of the drawer.

9. The combination with the casing having a drawer-receptacle therein, a drawer adapted to operate in the receptacle, and extension-supports mounted to operate in the drawer-receptacle having ways thereon, and guiding-grooves arranged adjacent to the ways, of supporting devices carried by the drawer and arranged to operate on the ways of the supports, and projections arranged to operate in the guiding-grooves adjacent to the ways for retaining the drawer and supports in coöperative relation.

10. The combination with the casing having a drawer-receptacle therein, a drawer adapted to operate in the receptacle, movable supports mounted to operate in the drawer-receptacle and devices for supporting the drawer on the supports, of guides secured to the casing having upper and lower ways thereon, and supporting devices carried by the supports arranged to coöperate respectively with the upper and lower ways of the guides.

11. The combination with the casing having a drawer-receptacle therein, a drawer adapted to operate in the drawer-receptacle, extension-supports arranged to operate in the drawer-receptacle and devices for sup-

porting the drawer on the supports, of guides arranged longitudinally in the drawer-receptacle having upper and lower ways thereon, rollers carried by the supports and arranged to operate on the upper ways of the guides for suspending the supports, and rollers carried by the supports in rear of the suspension-rollers and arranged to operate on the lower ways of the guides for preventing tilting of the supports.

12. The combination with the casing having a drawer-receptacle therein, a drawer adapted to operate in the receptacle, supports for the drawer arranged to operate in the drawer-receptacle, of guides arranged in the drawer-receptacle having upper and lower ways thereon, the upper ways having guiding-grooves extending longitudinally thereof, supporting devices carried by the supports arranged to operate on the upper ways and having portions arranged to coöperate with the guiding-grooves to prevent lateral displacement of the supports, and devices carried by the supports and arranged to coöperate with the lower ways of the guides.

13. The combination with the casing having a drawer-receptacle therein, a drawer adapted to operate in the drawer-receptacle, and extension-supports for the drawer arranged to operate in the drawer-receptacle, of guides arranged in the drawer-receptacle having ways at the upper sides thereof and guiding-grooves arranged longitudinally of the ways, and flanged rollers carried by the supports having portions arranged to operate on the ways and flanges to coöperate with the grooves for guiding the rollers on the guides.

14. The combination with the casing having a drawer-receptacle therein, and a drawer adapted to operate in the drawer-receptacle, of extension-supports arranged to operate in the drawer-receptacle having ways at their lower sides, and guiding-grooves extending longitudinally of the ways, rollers on the casing arranged to coöperate with the ways of the supports, and projections arranged to operate in the guiding-grooves of the supports.

15. The combination with the casing having a drawer-receptacle therein, and a drawer adapted to operate in the receptacle, of extension-supports arranged to operate in the drawer-receptacle having ways at their lower sides, rollers mounted on the casing in the forward portion of the drawer-receptacle, and arranged to coöperate with the ways of the supports, guides arranged above the supports having ways at their upper and lower sides, and rollers journaled on the supports near their rear ends and arranged to coöperate respectively with the upper and lower ways of the guides.

CARL ERNST.
